US00D528631S

(12) **United States Design Patent** (10) **Patent No.:** **US D528,631 S**
Gillette et al. (45) **Date of Patent:** **** Sep. 19, 2006**

(54) **PAN HEAD SHOWER HEAD**

(75) Inventors: **William J. Gillette**, Fort Collins, CO (US); **Timothy A. Bachman**, St. Paul, MN (US)

(73) Assignee: **Water Pik, Inc.**, Fort Collins, CO (US)

(**) Term: **14 Years**

(21) Appl. No.: **29/215,264**

(22) Filed: **Oct. 15, 2004**

Related U.S. Application Data

(63) Continuation of application No. 10/658,051, filed on Sep. 9, 2003, which is a continuation of application No. 10/021,852, filed on Dec. 12, 2001, now Pat. No. 6,641,057.

(51) **LOC (8) Cl.** **23-01**

(52) **U.S. Cl.** **D23/223; D23/229**

(58) **Field of Classification Search** D23/213, D23/223, 229, 230; 239/282, 283, 460, 394

See application file for complete search history.

(57) **CLAIM**

The ornamental design for a pan head shower head, as shown and described.

DESCRIPTION

FIG. 1 is a bottom perspective view of a first embodiment of a shower head showing our new design;

FIG. 2 is a bottom plan view of the shower head of FIG. 1; FIG. 3 is a right side elevation view of the shower head of FIG. 1, of which the left side elevation view is a mirror image;

FIG. 4 is a front elevation view of the shower head of FIG. 1;

FIG. 5 is a rear elevation view of the shower head of FIG. 1;

FIG. 6 is a top plan view of the shower head of FIG. 1;

FIG. 7 is a bottom perspective view of a second embodiment of a shower head showing our new design;

FIG. 8 is a bottom plan view of the shower head of FIG. 7; FIG. 9 is a right side elevation view of the shower head of FIG. 7, of which the left side elevation view is a mirror image;

FIG. 10 is a front elevation view of the shower head of FIG. 7;

FIG. 11 is a rear elevation view of the shower head of FIG. 7; and,

FIG. 12 is a top plan view of the shower head of FIG. 7. The broken line showing is for illustrative purposes only and forms no part of the claimed design.

UNITED STATES PATENT AND TRADEMARK OFFICE
CERTIFICATE OF CORRECTION

PATENT NO. : Des. 528,631 S

Page 1 of 1

APPLICATION NO. : 29/215264

DATED : September 19, 2006

INVENTOR(S) : William J. Gillette and Timothy A. Bachman

It is certified that error appears in the above-identified patent and that said Letters Patent is hereby corrected as shown below:

On the Title page (63), under "Related U.S. Application Data", after "Pat No. 6,641,057", please insert --which claims the benefit of 60/255,369, filed on December 12, 2000--.

Signed and Sealed this

Twelfth Day of December, 2006

A handwritten signature in black ink, appearing to read "Jon W. Dudas", is centered within a rectangular box with a dotted background.

JON W. DUDAS
Director of the United States Patent and Trademark Office
